MANUALLY AND FLUID PRESSURE
OPERATED VALVE

Anthony F. Schwendner, Ridley Park, Pa., assignor to Westinghouse Electric Corporation, East Pittsburgh, Pa., a corporation of Pennsylvania

Application November 19, 1949, Serial No. 128,355

3 Claims. (Cl. 137—641)

1

The invention relates to an oil-operated throttle valve and it has for an object to provide manually operable mechanical means for opening the throttle valve incident to starting, at which time the oil pressure is insufficient, and which mechanical means is automatically disconnected upon development of sufficient oil pressure.

The foregoing and other objects are effected by the invention as will be apparent from the following description and claims taken in connection with the accompanying drawings, forming a part of this application, in which:

Fig. 1 is an elevational view showing the throttle valve applied to a turbine;

Fig. 2 is a sectional view of the valve; and

Fig. 3 is a detail view of the releasable key for the hand wheel.

In the drawing, there is shown a steam turbine, at 10, having a steam supply conduit 11 provided with throttle and governing valves 12 and 14. As is customary, the throttle valve is normally held open by means of oil under pressure supplied to a space 15 from any suitable source, as by the orifice 16.

As shown, the space 15 is defined in part by the conduit 18 in communication with the lower portion of the throttle valve operating cylinder 19 having the piston 20 therein connected to the rod 21, carrying the movable throttle valve element 22. The piston 20 is normally held in upward position to hold the throttle valve open by means of oil under pressure supplied by the conduit 18, the force of such pressure acting upwardly on the piston 20 to hold the throttle valve open against the force of the spring 24 arranged above the piston.

The conduit 18 has the usual trip valve 25 associated therewith and tripped by the emergency governor 26 to response to over-speeding of the turbine, whereupon, due to sudden release of pressure below the piston 20, the latter is moved downwardly by the spring 24 to close rapidly the throttle valve. To enable the throttle valve to be opened when starting, at which time insufficient pressure is supplied by the conduit 18, manual means is provided for this purpose. Accordingly, the upper end of the cylinder has a cover 28 having a central threaded opening 30 in which there is arranged a threaded sleeve 31 coaxial with the rod 21 and the piston 20 and a hand wheel 23 is attached to the outer end of the sleeve, the sleeve extending inwardly of the cylinder and toward the piston 20.

The piston 20 has attached to its upper side the stem nut construction 32 having a socket 33

into which extends the spindle or stem 34. A ball thrust bearing 35 is retained in the socket 33 and it is connected to the lower end of the spindle 34. Thus, the spindle 34 has a swivel connection with respect to the piston 20 and the valve stem 21. The outer end of the spindle 34 has a channel 36 providing an abutment collar 37 having an inner abutment surface 38. The hand wheel has a latch member 39 pivoted thereto at 40 and having a notch 41 so that, with the piston 20 in its lowermost position and the sleeve screwed down by the hand wheel, the latch 39 may be positioned to be swung so that the notch 41 engages about the neck 36 with the upper abutment surface 42 of the latch engaged underneath the collar 38. A spring 43 is carried by the hand wheel and it is normally effective to swing the latch member 39 about its pivot 40 to clear the upper end of the stem 34.

With the latch member held in position back of the stem collar 37, the hand wheel 23 may be turned outwardly until sufficient friction is developed between the abutment surfaces 42 and 38 to hold the latch member in engaged position and against the force of its spring, the latch member being so held while the hand wheel 23 is operated to pull the throttle valve open against the force of the spring 34.

With the emergency governor latched in position to provide for development of pressure in the pressure space 15 and with the throttle valve opened normally to the extent required and in the manner just described, steam is admitted to the turbine for rotation of the latter; and, when sufficient pressure is developed in the space 15 to exert force on the piston against the spring 24 to relieve the normal force between the surfaces 38 and 42 the latch is released, whereupon oil under pressure supplied by the conduit 18 is adequate to move the piston to open fully the throttle valve.

While the invention has been shown in but one form, it will be obvious to those skilled in the art that it is not so limited, but is susceptible of various changes and modifications without departing from the spirit thereof.

What is claimed is:

1. A throttle valve for a turbine provided with an emergency governor, a piston operatively connected to the throttle valve; a casing structure including a cylinder for the piston; means for applying oil under pressure to the piston to exert opening force on the throttle valve; a spring interposed between a portion of the casing structure and said piston for exerting closing force on said

valve; the closing force exerted by the spring being substantially less than the normal opening force exerted by oil pressure on the piston; manual means including a sleeve operatively mounted in screw-threaded engagement in said casing structure; a hand wheel secured thereto and a latch mounted on the handwheel, a spindle rotatably secured to said piston and extending through said sleeve, said spindle having a collar engageable by said latch when said oil pressure is less than the force of said spring, so that the latch, when in engaged position, provides for opening the valve by rotation of the hand wheel when the oil pressure acting on the piston is inadequate for this purpose; and biasing means for tripping out the latch upon disengagement therefrom of said collar of the spindle when the force of oil pressure acting on the piston exceeds the force of the spring thereby providing for closing of the throttle valve by the spring when the oil pressure is removed.

2. A throttle valve provided with a stem for opening and closing it, a piston connected to the stem, a cylinder for the piston; said cylinder having a bottom through which the stem extends and a cover; a spring interposed between the cover and the piston for exerting valve-closing force on the latter; a passage for supplying liquid to the cylinder between the bottom and the piston for applying to the latter valve-opening force in opposition to the valve-closing force of the spring; a sleeve having threaded connection with respect to the cover and extending into the cylinder; a hand wheel attached to the outer end of the sleeve; a spindle having swivelled connection with respect to the stem and arranged to slidably extend through the sleeve; said spindle having an outer shoulder provided with an inner abutment face; a latch carried by the hand wheel and having an outer face engageable frictionally with the shoulder inner abutment face so that, with turning of the threaded sleeve and engagement of the latch and shoulder abutment faces to move the stem in a valve opening direction against the force of the spring, the spring exerts sufficient force frictionally engaging the abutment surfaces of the latch and of the shoulder to hold the latch and spindle in engagement; and a spring for moving the latch clear of the spindle upon sufficient reduction in frictional engagement of the latch and

shoulder abutment surfaces incident to opening force of liquid pressure applied to the piston.

3. In a throttle valve device for a turbine, the combination with a valve having a stem, of a piston connected to the stem; a cylinder for the piston; said cylinder having a bottom through which the stem extends and a cover; a spring interposed between the cover and the piston for exerting valve-closing force on the latter; a passage for supplying liquid to the cylinder between the bottom and the piston for applying to the latter valve-opening force in opposition to the valve-closing force of the spring; a sleeve having threaded connection in an opening of the cover and extending into the cylinder; a hand wheel having an apertured hub attached to the outer end of the sleeve; a spindle having swivelled connection with respect to the stem and arranged to slidably extend through the sleeve and said apertured hub; said spindle having an outer shoulder provided with an inner abutment face; a latch carried by the hand wheel and having an outer face engageable frictionally with the shoulder inner abutment face so that, with turning of the threaded sleeve and engagement of the latch and shoulder abutment faces to move the stem in a valve opening direction against the force of the spring, the spring exerts sufficient force frictionally engaging the abutment surfaces of the latch and of the shoulder to hold the latch and spindle in engagement; and a spring for moving the latch clear of the spindle upon sufficient reduction in frictional engagement of the latch and shoulder abutment surfaces incident to application of liquid pressure to the piston for opening the valve, said spindle being thereafter freely movable relative to said apertured hub according to variations in pressure of oil on said piston and regardless of the position of said hand wheel.

ANTHONY F. SCHWENDNER.
